E. NORTH.
UNDERREAMER.
APPLICATION FILED JUNE 20, 1917.

1,262,591.

Patented Apr. 9, 1918.

UNITED STATES PATENT OFFICE.

EDWARD NORTH, OF LOS ANGELES, CALIFORNIA.

UNDERREAMER.

1,262,591

Specification of Letters Patent. Patented Apr. 9, 1918.

Application filed June 20, 1917. Serial No. 175,943.

To all whom it may concern:

Be it known that I, EDWARD NORTH, a citizen of the United States, residing at Los Angeles, in the county of Los Angeles and State of California, have invented a new and useful Improvement in Underreamers, of which the following is a specification.

This invention relates to tools adapted to 10 enlarge the hole beneath the casing in the operation of drilling oil wells, water wells and the like.

Objects of this invention are ease of manufacture, simplicity of construction, 15 smoothness of operation, superiority of action in expanding and contracting, superior strength, greater ease of assemblage and security against accidental disassembling.

It is a feature of the invention that the 20 cutters are provided with flat-faced shanks that are seated in a flat-faced socket when the tool is expanded in operative position, and in which the upper portions of the shanks are held firmly by straight edges 25 contacting with flat faces when the tool is collapsed. By this construction the cutters are held firm and true when the tool is collapsed so as to cause less trouble as the tool runs down the casing.

An object is to gain simplicity and 30 strength of construction as compared with other under-reamers of a similar general design and in this connection to eliminate the small comparatively weak dove-tailing 35 in use in some former under-reamers. To this end I furnish this tool with an arrangement of feathers and steps of novel construction and thus provide bearing-surfaces and parts; of such strength as to be 40 practically unbreakable; at the same time making the tool stronger and much simpler in construction.

An object is to provide a superior underreamer in which all movable or working 45 parts are assembled and the requisite pressure or tension is put upon the spring, before said working parts are inserted in the body; slots for retaining keys being provided and so slanted on the lower sides that 50 as the keys are driven into place they ap-

ply a slight added pressure to the spring, thus insuring against lost motion in the cutters when the tool is in operation. I also propose to insure safety, in that a stop preferably in the form of a pipe inside the 55 cutter-retracting spring absolutely prevents the cutters from being pulled down far enough to come off of the retracting-head, and thus avoiding all danger that the cutters be lost in the well.

An object is to make an improvement in that the cutters, when contracted, are much more rigid in the body of the tool and will, therefore, cause less trouble in going down the casing, the advantage being due to the 65 difference in construction between a circular recessed body, as in certain earlier patents, in which, as the cutters are withdrawn, they lose contact with the body at all points but one, while in the present form of 70 my invention the side contact is maintained.

The invention includes the under reamer and various novel parts and combinations of parts particularly described and claimed herein.

Further objects and advantages may appear from the accompanying drawing, the subjoined detail description and the appended claims.

The invention may be carried out with 80 various forms of construction and I do not propose to limit the construction to the exact form shown although it is understood that the construction and arrangement of the various parts and faces are very im- 85 portant toward attaining in toto all the objects in view.

The accompanying drawings illustrate 90 the invention in a form I at present deem most satisfactory.

Figure 1 is an elevation of one side of the tool expanded.

Fig. 2 is a fragmental side elevation of the lower part of the tool shown in Fig. 1 turned quarter way around from Fig. 1.

Fig. 3 is a fragmental sectional elevation of the tool in the casing of a well. Dotted lines indicate positions of parts when the tool is expanded below the casing.

Fig. 4 is a fragmental view of the tool

shown in Fig. 3 from the side visible in Fig. 2, the body of the tool being shown in axial mid-section.

Fig. 5 is a bottom plan view from line 5 x^5 , Fig. 3.

Fig. 6 is an axial fragmental section of the tool body on line x^6 , Fig. 5.

Fig. 7 is a fragmental axial section of the tool body on line x^7 , Fig. 5.

Fig. 8 is a perspective of the outer side of one of the cutters.

Fig. 9 is a perspective of the inner side of one of the cutters.

Fig. 10 is a cross-section on line x^{10} , Fig. 15 4, looking up.

Fig. 11 is a bottom plan of the stock from which all other parts are omitted.

Figs. 1, 2, 6 and 7 are on one scale and Figs. 3, 4, 5, 8, 9 and 10 are on a larger 20 scale. Fig. 11 is on a scale intermediate the scales of the other views.

The tool body, stock or barrel 1 is preferably cylindrical in the main, and has the usual tool pin 2 and wrench square 3.

25 The stock 1 is provided with a central cylindrical bore 4 and with a downwardly flaring socket 5 opening downward at the lower end of the stock. Said socket has parallel flat upwardly reduced side walls 6 provided 30 with steps 7 and communicates with lateral openings 8 at the lower end of said steps.

Said socket is also provided with upwardly converging flat faces 9 having recesses 10 communicating with said lateral openings 35 8. The inner edges 11 of the steps on one side converge upwardly and are in parallelism with the upwardly converging inner flat faces 9 of the socket. The inner edges of the steps on the other side are likewise 40 constructed and arranged.

Each cutter 12 comprises a blade 13 having a flat inner face 14 and terminating in a shoulder 15. Said cutters also have shanks 16, each having an inner flat face 17 oblique 45 to the face 14 of the cutter blade. The outer face 18 of the shank is flat and in the form shown extends in practical parallelism with the produced axis of the cutter blade. Opposite faces 19, 19, of each shank are practically parallel to each other and are provided with feathers 20 extending from the flat inner face 17 of the shank toward the flat outer face 18 of said shank; and the outer edges 21 of said feathers are practically in parallelism with said outer base 18.

60 The feathers 20 are wedge-shaped, the upper ends being reduced and the space between the outer edges 21 of the feathers and the outer face 18 of the shank being of uniform width from end to end of the feathers and corresponding in width to the width of the space 7, so that when the shanks are seated, the ribs wedge into the space between the steps in conformity with the wedging

action of the shanks into the space between 65 the converging flat faces 9 of the socket. This construction greatly increases the strength and rigidity of the tool at the moment the blow is struck and allows an immediate yielding or retraction of the cutters 70 on the upstroke of the tool.

The shanks are provided with retainer seats 22 in the form of perforations that are shown as circular at the outer side of the shank and which flare inwardly toward the 75 oblique face 17 and terminate in grooves 23 to accommodate the suspending rod 24 which has a cutter support 25 in the form of a T head or projection at the lower end of the rod. The upper end of said rod is 80 fitted with a retainer in the form of a nut 26 threaded onto said rod to support the thrust against a washer 27 by the cutter supporting and retracting spring 28 which is mounted on the lower washer 29 that is 85 supported by a pair of keys 30 driven into seats 30' provided therefor in the stock above the downwardly flaring socket 5. Said seats are slots extending in parallelism with each other through the stock on opposite sides of the axis thereof and spaced apart to hold the keys 30 sufficiently apart to accommodate the supporting rod 24 between them; but arranged close enough together to support the washer 29 which in 90 turn supports the spring 28. Said suspending rod is provided with a shoulder 31 adapted to pass between the keys 30 and to support the washer 29 during the operation of assembling.

100 The upper walls of the key-ways are normal to the axis of the stock 1, and the lower walls of said key-ways are aslant from one to the other side of the stock to accommodate the wedge-shaped keys 30, so that when 105 the keys are inserted under the washer 29 and driven home into their seats there will be a slight wedging action to tighten said washer against the spring to increase the tension thereof so as to draw the cutters 110 more firmly into the seat therefor.

A stop 32 to limit the approach of the washer 27 and retainer or any equivalent thereof when the parts are assembled and the tool is in operation, is provided between 115 the washers 27, 29 and within the helical spring 28. Said stop is shown as a piece of pipe around the suspending rod and inside the cutter supporting spring.

The stock 1 is pierced with a hole 33 at 120 one side of the bore 4 and extending from side to side of the stock at one end of the key-slots 31, and the keys 30 are pierced to receive a pin 34 passed through the hole 33 when the keys are fully seated. Said pin 125 is preferably a piece of wire of sufficient size to hold the keys in place. Said wire is bent at its ends inside the recesses 35 at the

ends of the hole 33 to prevent the accidental displacement thereof. The washers are of greater diameter than the open space inside the coil spring.

- 5 To assemble the tool the lower washer 29 will first be applied to the supporting rod 24 and brought to rest upon the shoulder 31. Then the stop 32 will be put onto the supporting rod to rest against the washer 29 10 and the helical spring 28 will be applied to the rod outside of the stop 32, then the washer 27 will be put in place on the supporting rod and against the end of the spring 28, and then the nut 26 will be 15 screwed home to compress the spring. The spring 28 when not compressed will normally be almost as long as the length of rod between the shoulder 31 and the threaded end of the suspending rod, so that when the 20 nut is screwed home on the upper washer 27, the spring will be slightly compressed thereby before the nut is fully seated. The threaded portion 36 of the supporting rod is preferably just long enough to fully seat 25 the nut 26, so that said nut can be firmly screwed home slightly compressing the retracting spring 32.

When the supporting rod, the washers, stop, spring and nut have thus been assembled, the cutters will be adjusted to the ends of the T head 25 and the supporting rod with its nut, washer and spring will be inserted into the bore of the tool to bring the washer 29 beyond the key-ways and at the 30 same time bringing the shanks of the cutters together within the socket, the oblique flat faces 17 of the shanks being in contact with each other as shown in Fig. 1 in solid lines and in Fig. 3 in dotted lines. Then the keys 35 30 will be inserted and driven home, the first action of said keys as they are driven home being to wedge the lower washer 29 upward to compress the spring and draw the cutter shanks up into the socket therefor.

40 When the parts are thus secured together the keys are finally fastened by the wire pin 34 and the ends of the pin are bent over in the side recesses 35. The tool is then ready to be connected to the usual parts, 45 not shown, to complete a string of tools, and is thus ready to be inserted into the casing. For the purpose of inserting the tool into the casing, the cutters will be drawn down into the position shown in solid lines in Fig. 50 3, and the cutters will then be inserted into the casing with which the usual runners 37 contact. The tool may then be lowered and the runners will run down on the inside of the well casing until they escape from the 55 lower end of the casing. Thereupon the spring 28 will retract the cutters and the upper square edges 18 of the shanks will run on the flat converging faces 9, thus being drawn together and thereby expanding the

60 cutters into the position shown in dotted lines in Fig. 3. Thereupon the tool is ready for operation to ream out the hole beneath the casing.

When the tool is withdrawn from below the casing the upper edges of the runners 37 65 catch upon the casing and hold the runners while the stock ascends, thus compressing the spring, the resiliency of which 70 yieldingly holds the tips of the cutter shanks in the socket. When the shanks reach the 75 lower wider portion of the socket, the runners escape from the contact sufficiently to enter the lower edge of the shoe of the casing and run up inside the casing as is usual with 80 cutters of this class of tools while being withdrawn from a casing.

Among the features of novelty that have been disclosed particular attention is directed to the following:

85 Portions of the cutters fit into the recessed part of the body of the tool in which there are provided the steps or flanges of such great cross section as to practically obviate all chance of breakage. These flanges take the place of weaker dove-tailing in 90 other tools of somewhat similar type.

95 The rectilinear form of the upper part or shank of the cutter increases very greatly the strength at that point where it is necessary to bore it out to provide channels for the supporting rod and cross-head.

It is believed that no other under-reamer 100 the cutters of which rock upon each other; that is to say, under-reamers in which no intermediate or dividing wedge is used in expanding the cutters to working position, has cutters, the shanks of which have this form with its attendant advantages.

The construction of the body or barrel of the tool includes the specially-formed recess 105 in which the shanks of the cutters operate. The upper end terminates in the customary tool-joint. A cylindrical cavity of the required depth and of such diameter as may be necessary to take the suspending rod with 110 its surrounding stop of pipe, or otherwise, operating spring with bottom bearing, washer or otherwise, and compression nut, or other means of maintaining proper compression on the spring, is provided, extending upward from the top of the cavity, or recess, in which the shanks of the cutters operate.

115 The two tapering slots which pierce the body or stock in such position that wedge-shaped keys inserted in said slots, one on each side of the supporting rod, will engage the lower side of the bottom bearing, or washer support of the spring, the taper being such that as the key is forced to its ultimate position, a slight additional tension is put upon said spring so as to insure the cutters being held firmly in their operative position.

sition; these keys being kept from working loose by the piece of wire inserted in corresponding holes in the body and the keys.

The advantage claimed for this part of 5 the tool is the being able to take out or replace the working parts of the tool by means of these keys, or other similar means, such as screws.

The recess or cavity at the bottom of the 10 barrel is provided not only with recesses to fit and engage the steps on the shanks of the cutters so as to hold them rigid when in operation, but is so shaped as to bear against the upper ends of said shanks and thereby 15 reinforce the action of the steps and their corresponding recesses in preventing the closing together of said cutters when in operation.

The supporting-rod (which is preferably 20 made in one piece, and in T form, though it may be made straight, with a slotted head through which a key may be placed) has, as shown, an enlarged section (31) near the lower end, for the purpose of supporting 25 the lower bearing of the spring. This enlarged section is not essential, as any other means of holding the lower bearing of the spring against the pressure put on by the compression nut at such times as the under- 30 reamer is not assembled and ready for operation will be satisfactory.

I claim:—

1. An under-reamer having a flaring flat-faced stepped socket in its lower end and a bore extending upward from the socket; cutters having feathered shanks to conform to said socket when the cutters are expanded for under-reaming; said cutters being provided with orifices flaring inwardly; and 40 a supporting rod having a head in said orifices and a spring to retract said head toward the top of the socket; the feathers of said shanks being upwardly reduced and the outer feathered edges being in parallelism 45 with the outer face of the shank and the space between the outer edges corresponding with the width of the steps of the socket.

2. An under-reamer having a flaring flat-faced socket in its lower end and a bore extending upward from the socket; cutters having shanks to conform to said socket when the cutters are expanded for under-reaming, said cutters being provided with

orifices flaring inwardly, and a supporting rod having a head in said orifices, and a spring to retract said head toward the top of the socket; opposite side walls of said socket being recessed to receive the ends of the head when the same is fully retracted and the cutters expanded; said socket being provided with converging steps and said shank with upwardly reduced feathers for the purpose of assisting to resist the working blow and to release the cutters immediately upon the beginning of the upstroke. 65

3. An under-reamer comprising a stock having a socket in its lower end; and cutters yieldingly held in said socket and provided with shanks having feathers on their sides at the inner edges thereof; said socket conforming to the shanks and provided with steps to seat said feathers; the steps being of uniform width and the feathers upwardly reduced as and for the purpose set forth. 70

4. An under-reamer comprising a body provided with a central bore terminating in a socket at the end of the body and also provided with transverse key-ways, said socket having two parallel faces in continuation of said bore and two diverging faces between the outer edges of the parallel faces, said parallel faces being recessed, the recesses having rectilinear walls, said diverging faces being recessed, said recesses in the diverging faces having at the upper ends seats for the ends of a cross head, under-reaming cutters having shanks to conform to the socket and provided with orifices to receive the cross head and also provided with recesses communicating with said orifices to accommodate the cross head stem or rod; a cross head having its arms engaged in said orifices and adapted to engage the cross head seat and having a stem forming a suspending rod extending upward into the bore of the body; a spring surrounding said stem; means to retain the spring on the stem; and wedging keys in the key seats to support the spring-supporting means. 85 90 95 100

In testimony whereof, I have hereunto set my hand at Los Angeles, California, this 15th day of June, 1917.

EDWARD NORTH.

Witness:

JAMES R. TOWNSEND.
